(57) **CLAIM**

The ornamental design for a push-up bar, as shown and described.

DESCRIPTION

FIG. 1 is a perspective view of the push-up bar.

FIG. 2 is a front view of the push-up bar of FIG. 1, the rear view being a mirror-image thereof;

FIG. 3 is a left-side view of the push-up bar of FIG. 1, the right side view being a mirror image thereof;

FIG. 4 is a top view of the push-up bar of FIG. 1; and,

FIG. 5 is a bottom view of the push-up bar of FIG. 1.

The broken line showing of the push-up bar is included for the purpose of illustrating portions of the article and forms no part of the claimed design.

1 Claim, 5 Drawing Sheets
